UNITED STATES PATENT OFFICE.

JOHN JOHNSON, OF TAMPA, FLORIDA.

MEANS FOR FORMING SEPTIC TANKS.

Application filed March 19, 1925. Serial No. 16,770.

To all whom it may concern:

Be it known that I, JOHN JOHNSON, a citizen of the United States, residing at Tampa, in the county of Hillsborough, State of Florida, have invented certain new and useful Improvements in Means for Forming Septic Tanks, of which the following is a specification.

My invention relates to the manufacture of tanks, such as septic tanks of the type formed of a material which while in a plastic state is placed in a form and which when it has hardened forms the walls of the tank.

An object of the invention is to provide novel means for forming relatively heavy tanks of the character described in such manner that the tanks can be moved from the place at which they are formed to a desired place and placed in position for use quickly, easily and with but relatively little labor.

A further object of the invention is to provide novel means whereby tanks of a desirable size and shape can be formed accurately and quickly.

Other objects and advantages of the invention will be apparent from the following description, considered in conjunction with the accompanying drawings, in which:

Figure 1 is a perspective view of a structure embodying the invention,

Figure 2 is a vertical section through the structure shown in Fig. 1 and through a tank which has been formed therein,

Figure 3 is a section along the line 3—3 of Figure 2,

Figure 4 is a perspective view of the outer form which is comprised in the structure, and

Figure 5 is a perspective view of a tank formed in accordance with the invention, the tank being shown in upright position.

A structure adapted for use in the manufacture of tanks according to the invention includes a guiding and supporting frame designated generally at 1 which comprises a pair of vertical corner guide posts or uprights 2, a second pair of vertical corner guide posts or uprights 3 and a pair of intermediate or side guide posts or uprights 4.

Each of the corner guide posts or uprights 2 or 3 is right angular in horizontal sectional contour as best seen in Fig. 3. Each guide 4 is formed of two similar vertical members 4^a each having a flat inner vertical face and a third vertical member 4^b which is

interposed between the associated members 4^a and is connected to the latter in any suitable known manner so that the flat inner faces of such associated members 4^a lie in the same plane beyond which the vertical inner edge portion of the member 4^b extends as indicated at 5. The portions 5 of the members 4^b may be considered as being ribs on the inner faces of the guides 4 and the remaining portions of the members 4^b and the associated members 4^a may be formed integrally with one another, if desired.

The end portions of the respective guides 2 are held in spaced edgewise alignment by an upper end bar 6 and a lower end bar 7 and the respective end portions of the respective guides 3 likewise are held in spaced edgewise alignment by similar upper and lower end bars 6' and 7' respectively. The side portions of the adjacent guides 2 and 3 and the guide 4 which is disposed therebetween are connected together by side bars 8 so that the inner faces of the side portions of the guides 2 and 3 and of the members 4^a—4^a of the guide 4 at each side of the frame 1 will lie in the same vertical plane and the inner edge portion 5 of the guide 4 at that side of the frame will extend inwardly of the frame beyond that plane. The respective guides 4 also may be connected together adjacent to their upper ends by a transverse edgewise disposed bar 9 which extends transversely of the frame between the adjacent or inner edges of the portions 5 and lies in the plane of the latter.

The frame 1 supports or is attached at its upper end to a platform or floor 10 which has an opening 11 therein substantially co-extensive in area with the cross sectional area of the vertical guideway which is defined by the corner guides 3 and the adjacent members 4^a and the portions 5 of the members 4^b of the guides 4. The platform 10 also has an opening 12 substantially co-extensive in area with the cross sectional area of the vertical guideway which is defined by the corner guides 2 and the adjacent members 4^a and portions 5 of the guides 4.

A hollow core 13 is slidable vertically in the first mentioned guideway from position below the level of the platform 10 until a portion of the core extends above the level of the platform 10. A core 14 is slidable in the second-named guideway from position below the level of the platform 10 until the core 14 has been raised so that a portion

thereof extends above the level of the platform 10 in a distance equal to the length of the similarly positioned upper portion of the core 13. The platform 10 may have 5 pulleys 15 depending therefrom and cables 16 which are trained about the pulleys may be connected at one end to attaching elements 17 carried by the cores and may be provided at their other end with weights 18 balancing the weights of the cores so that 10 the latter may be easily moved in the guideways from position below the level of the platform to position to extend above the level of the latter, as shown in Fig. 1, or vice versa. The cores 13 and 14 may be releasably secured in raised position as shown in Fig. 1 in any suitable manner as by means 15 of blocks resting upon horizontally alined side bars 8 as indicated at 19 in Figs. 1 and 2.

Each core 13 or 14 is substantially rectangular in cross sectional contour and each has one end wall thereof offset inwardly for part of its width as indicated at 20 for the 20 core 13 and at 21 for the core 14. A space thus is defined at 22 between the plane of the offset portion 20 and the plane of the outer face of the remainder of the one end wall of the core 13 for the reception of an auxiliary 25 core 23 which is shown as being a solid member adapted to be received within the space 22 so that inner vertical face of the core 23 will be spaced from the offset portion 20 of the one end wall of the core 13 and the outer 30 face of the core 23 will lie in the plane of the remaining portion of the end wall of the core 13 while the side walls of the core 23 will be spaced from the walls which merge the offset wall 20 into the remaining portion 35 of the one end wall of the core 13.

A core 24 similar to the core 23 is adapted to be positioned in the space which is provided by offsetting the portion 21 of the one end wall of the core 14 in the same position 40 in respect to the corresponding walls of the core 14 as the position of the core 23 bears to that of the core 13.

The cores 23 and 24 may be secured in the hereinbefore described positions in respect 45 to the cores 14 and 13, respectively, by suitable means, such as the bolts 25 carried by supporting members 26 which are supported at the lower ends of the respective cores. The cores 13 and 14 are closed at their upper ends by top plates 27 and 28, respectively.

A base 29 which is movably supported upon the platform 10, as by means of rollers 30, has an opening 31 co-extensive in area with the opening 11 and a second opening 32 co-extensive in area with the opening 12, the openings 31 and 32 being located relatively to each other so that the base can be disposed on the platform 10 with the opening 31 in register with the opening 11 and with 55 the opening 32 in register with the opening

12. The cores will then extend through the openings 31 and 32 above the level of the base 29 as shown in Figure 1.

An outer form 33 comprises a pair of similar substantially rectangular sides 34 70 and a pair of substantially rectangular ends 35. The sides 34 and the ends 35 are provided with co-engaging stop blocks or bars 36 and 37, respectively at the meeting portions thereof when the ends 35 are disposed in parallel relation between the sides 34 and in contact with the latter adjacent to the ends thereof. Clamps 38 comprising bars spanning the sides 34 at the upper edges of the latter and having depending end portions 38^a extending in contact with the outer faces of the sides for a slight distance from the upper edges of the latter tend to clamp the sides 34 to the ends 35 and to prevent relative movement of the sides and ends of 80 the outer form. Each side and end of the outer form may be formed of a plurality of boards 34^a or 35^a connected and braced by vertical boards or braces 34^b or 35^b.

The sides and ends of the outer form may 90 be disposed in spaced relation to the corresponding walls of the cores both because of the dimensions of the sides and ends of the outer form and the connection of the sides and ends of the outer form with each other 95 and because of the engagement of lugs 39 carried by the sides and ends of the outer form to depend below the lower edge thereof with sockets 40 in the base 29. The cores 13 and 14 are held spaced apart at their adjacent ends because of the engagement of the lower end portions of the cores with opposite sides of the portions 5 of the guide members 4.

From the foregoing description of the various parts of the device the operation thereof may be readily understood. Concrete or like material is poured at the upper end of the outer form into the space between the sides of the outer form and the sides of cores 13-14, between the one end of the outer form and the outer end of the core 13, and between the other end of the outer form and the adjacent walls of the core 14 and core 24. Concrete or like material also is poured 110 between the inner end of the core 14 and the adjacent ends of the core 13 and core 23, between the core 23 and the core 13, between the core 24 and the core 14, and across the upper ends of the cores 13 and 14, thus providing a tank 41 disposed in inverted position and having a bottom 42, end walls 43, side walls 44, a transverse partition 45, and baffles 46 and 47 respectively carried by one end wall 43 and the partition 45 and extending from the plane of the upper edge of the tank for part of the height of the latter. Filler blocks (not shown) may be placed upon the auxiliary cores 23 and 24 after the spaces between the auxiliary cores 115 120 125 130

- and the main cores have been filled so that the partition 45 and the baffles 46 and 47 may be formed as shown in Figure 5. Small core pieces (not shown) may be provided between 5 the ends of the outer form and the adjacent ends of the main cores 13 and 14 and between the main cores to provide openings 48 in the upper portions of the end walls and the partition of the tank, the openings 48 10 through partition 45 and the one end wall of the tank being in communication with the spaces defined by the baffles 46 and 47, respectively, in conjunction with the associated wall of the tank.
- 15 When the tank has been formed in inverted position in the manner described, the cores 13, 14, 23 and 24 are lowered beneath the level of the base 29 and the latter is then moved along the platform to a desired place, 20 at which the tank is overturned from the base by any suitable known means so that it will rest upon its bottom and in position for use. A slab (not shown) may be formed of concrete in an ordinary manner and employed as a cover for the tank.

Obviously, the invention is susceptible of embodiment in forms other than that illustrated in the accompanying drawings and I, therefore, consider as my own all modifications and adaptations thereof that fairly fall within the scope of the appended claims.

I claim:—

1. An apparatus adapted for use in forming a vessel of a plastic material, comprising 35 a platform having an opening therein, a base resting upon the platform and having an opening in register with the opening in the platform, a core adapted to move vertically through the registered openings in the platform and base to protrude above the level of the base, said core being of slightly less area in cross section than the opening in the base, said core having a re-entrant portion at one end thereof, an additional core received in the 40 space within said re-entrant portion of the first core in spaced relation to the walls of said re-entrant portion, an outer form open at its upper end and disposed on the base in spaced relation to the core, and a guide

frame beneath said base for preventing lateral movement of said core during the vertical movement thereof. 50

2. An apparatus of the character described comprising a platform having a plurality of openings, a base supported on said platform and having openings corresponding in area and relative arrangement with the openings of the platform and the base, corresponding openings of the platform being in vertical alinement, a core for each 55 opening of the base, means for guiding said cores for vertical movements to and from position to extend through the corresponding openings of the base above the level of the latter, means whereby said cores may be held in position to extend above the level of the base, an outer form supported on the base in position to encompass all of said cores, said outer form being open at its upper end, said base having notches therein 60 and said form having lugs depending therefrom for engaging with said notches to hold said form in spaced relation to said cores, each of said cores being hollow and being substantially rectangular in cross sectional 65 contour and closed at its upper end, each core having a re-entrant portion in one end wall thereof and a solid core received in the space which is defined by the walls of said re-entrant portion, said solid core being disposed in spaced relation to the walls of said 70 re-entrant portion. 75

3. In an apparatus of the character described, a hollow core closed at its upper end and being substantially rectangular in cross 80 sectional contour, said core having one end wall thereof formed with a re-entrant portion, a solid core received in the space which is defined by said re-entrant portion in spaced relation to the walls of the latter, 85 said solid core terminating at its upper end short of the upper end of the first core, and an outer form encompassing said cores and having walls disposed in adjacent spaced relation to the outer walls of said cores, said 90 form being open at its upper end. 95

JOHN JOHNSON.
